PACKAGING FILLING YARN

George A. Early, Old Orchard, Maine, assignor to
Pepperell Manufacturing Company, Boston,
Mass., a corporation of Massachusetts

Application June 15, 1939, Serial No. 279,313

1 Claim. (Cl. 242—16)

This invention relates to methods and apparatus for spinning and/or packaging yarn for filling shuttles and its object is to provide a novel method and apparatus which increase by as much as 30% or more the amount of yarn that can be carried by the conventional shuttle. I have achieved that result by winding the yarn on the bobbin in apparatus which presents the combination of a spindleless driving mechanism and a bobbin to be used therein that is solid rather than axially bored as heretofore, and thereby is of considerably smaller external diameter and of larger capacity than prior hollow bobbins used on spindles. To increase further the amount of yarn on the bobbin I wind it under strong tension and where the yarn is a spun yarn, such as cotton or the like, I complete the spinning before winding the bobbin so that during such winding the yarn has sufficient strength to withstand the tension without breaking.

In the drawing:

Fig. 1 is a diagrammatic representation of a spinning frame;

Fig. 2 is a diagrammatic view of winding apparatus suitable for my purposes;

Fig. 3 is a side view of my novel bobbin; and

Fig. 4 is a section on the line 4—4 of Fig. 3.

I have illustrated in Figs. 3 and 4 a bobbin of novel construction embodying my invention by which, in part, I am able to increase considerably the amount of yarn that can be carried by a filling shuttle. The principle of my bobbin may be embodied in bobbins of various shapes and sizes for packaging cotton, rayon or other yarns. For purposes of illustration only, I have shown a cotton bobbin approximately 8 $\frac{1}{4}$ inches long. It has a head 42 which may be of usual size, shape and construction (approximately 1 inch external diameter) and with the conventional rings 100. The tip 52 at which the opposite end of the bobbin terminates being enlarged obviates fluffing off of the yarn.

The major portion 108 of the shank of my bobbin has an unusually small external diameter. As will appear, the method which I employ for packaging the yarn on the bobbin obviates the use of a spindle so that the bobbin shank need not be hollowed to receive a spindle as heretofore. Thus, the head cavity 102 terminates at 104 and the shank is solid throughout its entire length. The short hole 106 in the tip 52 accommodates the usual devices on the lathe in which the bobbin is turned. As a result of this solid shank construction, the external diameter of the major portion 108 of the shank may be in the

neighborhood of $\frac{3}{8}$ of an inch or less, as contrasted with an external diameter of $\frac{5}{8}$ of an inch or more in a conventional bobbin of this size and shape. This substantial reduction in size of the major portion of the bobbin shank effects a very substantial increase in the length of yarn that may be carried by the bobbin and yet readily received within the cavity of the conventional shuttle.

The bobbin illustrated is of the type adapted for an automatic shuttle changing loom having the conventional feeler mechanism which detects a depleted package by feeling the package adjacent the head end portion of the shank designated 110. To coordinate with that type of feeler mechanism, I enlarge the portion 110 of the shank to the necessary size, about $\frac{5}{8}$ of an inch in diameter in the bobbin shown. The portion 110 may be conveniently an inch and a half long in a bobbin of the type illustrated and merges, by the receding steps 112, with the main portion 108 of the shank which may be in the neighborhood of 4 $\frac{1}{4}$ inches long. It will, of course, be understood that these details will be varied depending upon the type of feeler mechanism employed and that where none is used the shank may be of the minimum diameter throughout its entire length, or it may taper slightly as is conventional. Indeed all of the foregoing dimensions are merely illustrative as they may be varied considerably and my invention is to be limited only as the claims require.

To obtain the maximum length of filling yarn in the shuttle package, my method of spinning and/or winding provides certain steps to be performed, preferably employing my novel bobbin above described. If the yarn is of a type that does not require spinning, such as filament rayon, the method steps of my invention will pertain only to winding on the bobbin, as illustrated in Fig. 2, but for spun yarns of cotton, rayon and the like my method provides preferred steps of spinning and bobbin winding.

In Fig. 1 I have diagrammatically illustrated a machine of suitable type for spinning yarn in accordance with the method aspect of my invention. If, according to the system conventionally employed for spinning the given type of yarn, there is more than one spinning operation, such as an initial spinning on a roving frame and a final spinning on a ring spinning frame, the apparatus of Fig. 1 is the machine on which the last spinning operation is effected and it may be a roving frame or, as illustrated, a ring spinning frame. The creel 2 has a large number of bob-

bins 4, of yarn or roving to be spun. At 6 are indicated the drafting rolls to draft the filaments 8 which pass thence through a pigtail eye 10 and traveler 12 to the package 14. The traveler 12 as usual moves on the ring 18 mounted on the ring rail 16 given a suitable traverse motion vertically of the bobbin as the package grows. At 20 is a whirl for rotating the spindle 22 on which the core of the package 14 is mounted.

All of the foregoing details may be of conventional construction except that the package 14 is preferably two, three or more times as large as could be received within the filling shuttle. The package may conveniently conform to the size of the usual warp bobbin and, indeed, the spinning frame 18 may be a warp spinning frame.

The package 14 of spun yarn is removed from the spinning frame and is rewound as illustrated in Fig. 2. The creel 30 carries spindles 32 on which preferably several packages 14 are placed and the yarn from each package is wound on a bobbin 40 of the construction above described. The head 42 of the bobbin is received within a cup 44 secured to shaft 46 power rotated from a suitable power source, as indicated by the pulley 48. Within the cup 44 is a layer of resilient material 50 against which the bobbin is pressed from its opposite end 52. The tip 52 is received within a second cup 54 carried on a shaft 56 having a free sliding fit in an orifice 58, drilled in the frame. A spring 60 interposed between a sleeve 62, secured to shaft 56, and frame 64, yieldingly urges the cup 54 in the direction of cup 44 to press bobbin head 42 firmly against the resilient layer 50. Suitable means, such as a collar 66 or the like, fixed to the end of shaft 56 projecting outside of frame 64, prevents the withdrawal of the shaft from the frame.

To insert the bobbin the cup 54 is retracted against the pressure of spring 60, the head 42 of the bobbin is inserted in cup 44 and cup 54 is released against the bobbin. As a result of the pressure of head 42 on the material 50, there is sufficient friction to drive the bobbin without slippage. A thrust bearing 67 having plate 69 concaved to receive the tip 52 of the bobbin freely permits such rotation.

Yarn drawn off the end of bobbin 14 is threaded through the guide 78 and through the friction disks 72 and 74. These friction disks may be of conventional construction, composed of pairs of convex disks spring pressed against each other as indicated. After passing through guides 78 the yarn is threaded through the eye 78 of a plate carried on rotating screw 79 operated to effect a traverse motion as the yarn is wound on the bobbin to form the package represented at 80. The external diameter of the portion 168 of the shank is no greater than one-half the external diameter of the package.

It will be noted that the driving means for the bobbin in the winder eliminates the use of a spindle, thereby effectively utilizing a bobbin with solid shank and hence of unusually small external diameter and large yarn capacity. The tension devices 72 and 74 further increase this quantity of yarn and as the spinning of the yarn, if any, is completed before winding on to the bobbin the yarn has sufficient strength to withstand this tension.

I claim:

25 In apparatus for packaging yarn for filling shuttles, the combination of a yarn receiving core having a head of predetermined diameter, a spindleless driver engaging the head to rotate the core to wind yarn thereon, a shank forming a portion of said core, which, throughout the major portion of its length, is solid in cross section and of a thickness less than approximately one-half the diameter of the head, a tip, on the opposite end of the shank from the head, of a thickness exceeding that of the shank to present a shoulder for minimizing fluffing off of the yarn over the tip, a cup adapted to support said tip, and means 30 for guiding yarn into direct engagement with the shank throughout its entire length to form a package which directly engages the shank and which throughout the major portion of its length has an internal diameter less than approximately one-half the external diameter of the head.
